UNITED STATES PATENT OFFICE.

ARTHUR J. BOYNTON, OF LORAIN, OHIO.

CHECKERWORK FOR HOT-BLAST STOVES.

1,243,484.

Specification of Letters Patent. Patented Oct. 16, 1917.

Application filed February 17, 1917. Serial No. 149,289.

To all whom it may concern:

Be it known that I, ARTHUR J. BOYNTON, a citizen of the United States, and resident of Lorain, in the county of Lorain and 5 State of Ohio, have invented certain new and useful Improvements in Checkerwork for Hot-Blast Stoves, of which the following is a specification.

This invention relates to the construction 10 of hot blast stoves and more particularly to the construction of the stove checkerwork.

As constructed heretofore, it was the practice to make the transverse dimensions of the vertical passages in the checkerwork of 15 the hot blast stoves somewhat larger than that which is most economical from the standpoint of hot-blast heating capacity. This was done to lessen the frequency with which accumulations of flue dust from the 20 vertical surfaces of the passages must be removed, and reduce the cost of cleaning the stoves.

To reduce the size of the vertical passages requires increase in the thickness of the 25 bricks at the expense of heating surface or else reducing the size of the bricks and greatly increasing the number of joints in the integrated checkerwork. To lessen the thickness of the bricks of which the checkerwork is formed decreases the bearing surfaces of the individual bricks so as to impair 30 the durability of the checkerwork.

The transverse dimensions of the vertical 35 passages were determined by experiment as to the time interval in which the surfaces of the passages became clogged to an extent requiring cleaning, a small passage necessitating more frequent cleaning than larger ones.

40 The thickness of the bricks forming the checkerwork was determined largely by the crushing strength of the refractory material of which they are formed, so that the thickness cannot be lessened beyond that which will give an ample bearing surface.

45 The greater the heating surface of the stove checkerwork the greater the heating capacity of the stove will be, but at the same time the number of joints in the integrated 50 structure will be very materially increased by the use of the smaller passages unless the heating capacity is sacrificed by making the bricks thicker than necessary.

55 In modern blast furnace plants the combustible blast furnace gases burned in the stoves in heating the checkerwork are dry cleaned or washed so that most of the finely

divided solids in blast furnace gases as received from the furnaces are removed before being burned. So the same necessity for 60 large passages in the stoves in cleaning the stoves does not exist. The life of the checkerwork in such stoves extends over long time intervals, and the cost of relining a 65 stove and supplying new checkerwork is very great.

The primary object of the invention is to provide a hot blast stove checkerwork of improved construction whereby the heating 70 capacity of the stove is materially increased without increase in the number of joints or decrease in the strength of the integrated checkerwork.

Another object of the invention is to provide novel means for increasing the heating 75 capacity of existing stoves at a minimum expense and without disturbance of the stove checkerwork.

A further object of this invention is the provision of a stove checkerwork having the 80 novel constructions, combinations, and arrangements of parts shown in the drawings, to be more fully described hereinafter and to be particularly pointed out in the appended claims.

85 My invention consists in the provision of a refractory checkerwork having a series of vertical passages formed therein with the ends of the bricks of the checkerwork in overlapping or interlocking engagement so 90 as to integrate the structure and in providing in the vertical passages vertical partitions formed of superposed bricks which are independently supported, are separate from the integrated checkerwork and which 95 are maintained in superposed position by contact with the side surfaces of the vertical passages.

Referring now to the drawings forming part of this specification, Figure 1 is a 100 horizontal section showing a hot blast stove having a well-known and preferred arrangement of checkerwork as modified to embody my invention.

Fig. 2 is a perspective view showing details in a preferred construction and arrangement of the partitions in the passages of the checkerwork as made in accordance 105 with this invention.

Fig. 3 is a perspective view showing a 110 checker brick made and adapted for use in forming diagonal partitions within the stove checkerwork in accordance with my invention.

In the accompanying drawings the numeral 2 designates the cylindrical metal shell of a hot blast stove which is provided with the usual refractory lining 3. The 5 stove shown has a side combustion chamber 4 and checkerwork chamber (designated generally by the numeral 5) which are formed in the refractory lining 3, a solid wall 6 separating the chamber 4 from the 10 chamber 5. A removable lining wall 7 is provided in the combustion chamber 4.

The space comprising the checkerwork chamber 5 is filled with the checkerwork which is built of rectangular bricks 8 having 15 notched ends 9 which overlap and which are laid, without grout or mortar, to form a multiplicity of vertical passages 10 (see Fig. 2), these passages extending from a point a short distance above the bottom of the stove 20 to a point near its top.

Within the vertical passages 10 of stove checkerwork made in accordance with my invention partitions are formed by superposed bricks 11 which extend vertically 25 within the passages 10 and are supported at the lower end of the vertical passages 10 in any suitable manner. As shown the bricks 11 forming the partition have beveled ends and extend diagonally from corner to corner 30 of the rectangular passages 10, the chamfered faces 12, 12 of the bricks contacting with the side surfaces of the bricks 8 to maintain the superposed bricks 11 in vertically alined position. In this way the 35 heating surface of the stoves is materially increased at slight expense and without adding to the number of joints in the loosely bonded checkerwork or necessitating any reduction in the thickness or other dimensions 40 of the bricks forming the checkerwork.

It will be noted by reference to Fig. 2 that the notched ends 9 of the bricks 8 are in interlocking or overlapping engagement so as to form a loosely bonded or integrated 45 structure. That is to say, the individual bricks 8 forming the checkerwork are tied together by their overlapping notched ends so that the structure must be razed to remove any particular brick other than those in the 50 top course of checker bricks. It will be obvious, however, that an integrated checkerwork may be built in other approved ways.

In constructing stoves embodying my invention, the partition bricks 11 are inserted 55 within the rectangular vertically extending passages 10 as the passages are formed. With existing stoves the bricks 11 are inserted within the passages 10 from the top of the stove, being lowered within the 60 passages and positioned one on top of another to form the diagonal partitions, without disturbing the bricks 8 of the checkerwork.

The advantages of my invention will be appreciated by those skilled in the art. By means of my invention the heating capacity 65 of the hot blast stoves is materially increased (in some cases as much as forty per cent.) in a simple and highly novel manner, at comparatively small expense and with existing materials. The invention is applicable to existing stove constructions without alteration of the stove checkerwork as well as to new stove structures.

Modifications in the construction and arrangement of the checkerwork and the partitions within the vertical passages of the checkerwork may be made without departing from my invention as defined in the appended claims.

I claim:—

1. In a hot blast stove, an integrated checkerwork having a series of vertical passages therein and separate and independently supported partitions within at least part of said vertical passages, said partitions being loosely mounted in the passages and being maintained in vertical position by contact with the side surfaces of said passages.

2. In a hot blast stove, an integrated checkerwork having a series of vertical passages therein and separate and independently supported partitions within the passages, said partitions being held in place by contact with the side surfaces of said 95 passages.

3. In a hot blast stove, a checkerwork comprising an integrated structure having a plurality of vertical passages therein and separate partitions within at least part of 100 said passages, said partitions being supported independently of the integrated structure and being maintained in vertical position by contact with the side surfaces of said passages.

4. In a hot blast stove, checkerwork having vertically extending rectangular passages therein and partitions within said passages, said partitions having ends engaging with the side surfaces of the passages.

5. In a hot blast stove, a checkerwork having vertically extending rectangular passages therein, and diagonal partitions within said passages, said partitions having chamfered ends engaging with the side surfaces of the passages at the corners thereof.

6. In a hot blast stove, an integrated checkerwork having a series of vertical passages therein and separate and independently supported partitions within the 120 passages.

In testimony whereof I have hereunto set my hand.

ARTHUR J. BOYNTON.
